UNITED STATES PATENT OFFICE.

EDWARD KINSELLA AND HARRY EDWARD BELLAIRS YOUNG, OF SPONDON, NEAR DERBY, ENGLAND, ASSIGNEES TO CELANESE CORPORATION OF AMERICA, A CORPORATION OF DELAWARE.

SPINNING APPARATUS FOR ARTIFICIAL YARNS OR THREADS.

Application filed November 28, 1925, Serial No. 71,882, and in Great Britain December 28, 1924.

This invention relates to new or improved cap twisting and winding apparatus for twisting and winding in cop or pirn form artificial yarns or threads of filaments of cellulose acetate or other cellulose esters of cellulose ethers continuously with their production by the dry or evaporative method of formation, usually known as "dry spinning".

- 10 A prior British specification No. 198023 and the specification of the corresponding U. S. application Serial No. 615,682 filed 29 January, 1923, have described and claimed the cap twisting and winding of such threads 15 or yarns continuously with their production by dry spinning, and according to the said specifications the threads or yarns may be cap-spun and wound in any desired wound form.
- 20 The present invention aims to provide improved forms of apparatus for the production of cops or pirns on the dry spinning métier or apparatus.
- 25 As is known, cops or pirns (hereinafter referred to as cop wound packages) are formed by the superimposition of two motions, namely an up and down traversing or "chasing" motion and a slow progressive feed or lift for building the cop or pirn.
- 30 It is very desirable, in order to reduce waste and to avoid stopping the dry spinning métier for dosing, that one shall be able to control the starting and stopping of the cop or pirn building feed or motion individually for each spindle, or at most for 35 two adjacent spindles.

It is also very desirable to wind at a high rate of speed and to have, in forming the cops or pirns, speeds of traverse or "chasing" motion much higher than those which are used with ordinary slow moving cop winds of cap spinning worsted frames.

In apparatus according to the present invention, the building feed mechanism is 45 combined with means for putting the feed into and out of engagement or operation for each spindle, (or it may be each pair of adjacent spindles) so that the starting and stopping of the building feed can be controlled individually for each spindle, (or it 50 may be for each two adjacent spindles), thereby allowing the slow lift for any spindle (or pair of adjacent spindles) to be

commenced independently of the remainder.

It is to be understood that the slow building feed or lift may be imparted either to the cap spindles or to members which carry the bobbins, tubes or like thread-carriers, and that the cap spindles or the said members, as the case may be, may either receive the slow building feed only or may receive both the slow building feed and the chasing motion as before mentioned. When the building feed is imparted to the cap spindles alone, the chasing motion is imparted to 55 members carrying the cop or pirn tubes, bobbins or the like, and vice versa.

According to the further part of the invention, instead of employing a continuous traversing rail or bar extending all along the dry spinning métier and actuated by a single or common traversing cam or apparatus to impart the rapid chasing motion to the cops or pirns, or to the cap spindles as the case may be, we preferably employ a line or series of separate traversing bars or members, each serving to impart the traverse to two adjacent cops or pirns or to two adjacent cap spindles, as the case may be, or it may be to each individual cop or pirn, or each individual cap spindle, these traversing bars or members each receiving the traversing or chasing motion from a separate cam or traversing device. Such employment of separate traversing bars or members permits more readily of the very rapid up and down traverse which is required in winding cops or pirns of dry spun artificial thread continuously with their production at high speed as before referred to.

In any of the forms of apparatus according to the invention in which the cap spindles receive a building feed motion, the thread guides disposed vertically above the cap spindles and serving to lead the threads down to the caps are preferably in connection with the cap spindles or otherwise arranged to rise together with their corresponding cap spindles, so as to maintain the "balloon" of thread at a constant height in relation to the cap.

Other features of the invention will appear from the succeeding description and from the appended claims.

The accompanying drawings illustrate by way of example two forms of apparatus ac-

cording to the invention, it being understood that these are given as examples only and are in no way limitative.

Figs. 1 to 7 illustrate a form of apparatus in which the cop or pîrn building feed is imparted to the cap spindles and the traversing or chasing motion is imparted to the cops or pîrns, while Figs. 8 and 9 illustrate a form wherein the building feed is imparted to the cops or pîrns, the chasing motion being imparted to the cap spindles.

The improved forms of cap or pîrn winding apparatus shown are supposed as applied on a métier of the character indicated in the said prior British specification No. 198023, and U. S. specification Serial No. 615,682, the threads of associated filaments formed in the métier casing being led from the métier casing (not shown) and fed to the apparatus for winding the cops or pîrns.

Fig. 1 is a diagrammatic sectional side elevation of the first form of apparatus, showing the thread fed to the cop or pîrn winding device by a feed roller or godet arranged and driven in the same manner as indicated in the previous British specification 198023 and U. S. specification Serial No. 615,682 and the whorls of the winding apparatus being also driven in a similar manner to that indicated in the said specification.

Fig. 2 is a front elevation of a portion of the improved cop or pîrn winding apparatus, showing the feed motion shaft and the chasing motion shaft, and four of the cap spindles with the means for driving the spindles from the feed motion shaft and for throwing the feed in and out for the individual spindles; and also the short traversing bars carrying the whorls and the cop or pîrn tubes which co-operate with the spindles, and also the means for imparting the chasing or traversing motion to these traversing bars from the chasing motion shaft. It is understood that the feed motion shaft and the chasing motion shaft may extend for any desired length along the métier and serve for operating any desired number of cap spindles and traversing bars arranged in the same way.

Fig. 3 is a vertical section on the line 3—3 Fig. 2.

Figs. 4, 5 and 6 are respectively a side elevation, a front elevation and a plan view of a housing member fitted with spring-loaded caps or cover plates, the body of the housing member and the spring-loaded caps or cover plates being formed with corresponding half bearings for two spindles, so that when the caps or cover plates are put on to the housing body the bearings or guides for guiding the respective spindles in their rise for the building feed are constituted.

Fig. 7 is a detail sectional view of one of the whorls with its cop or pîrn carrying sleeve or tube, and showing the mounting of the whorl on the short traversing or chasing

bar, and the cap spindle passing up through the whorl and its sleeve or tube.

Fig. 8 is a front elevation of a portion of the cop or pîrn winding apparatus according to the second form (wherein the cap spindles receive the chasing motion and the cops or pîrns receive the building feed). Similarly to Fig. 2 this figure likewise shows a length of the apparatus corresponding to four spindles. 75

Fig. 9 is a part-sectional end elevation of Fig. 8.

Referring first to Figs. 1 to 6, the cap spindles 1, each carrying a removable cap 2 are arranged in a row along the front of the métier and are mounted in guides or bearings so as to be free to move vertically for the slow cop or pîrn building feed. The spindles 1 are raised very slowly to provide this feed by means of a feed motion shaft 3 running all 85 along the métier and caused to rotate at a suitably slow speed, for instance about one revolution per hour. A series of clutches 4 on the shaft 3, one for each spindle 1, and each connected by a chain 5 to a lug 6 or other suitable part bolted or otherwise attached or connected to the corresponding spindle as at 7 (see Fig. 3), enable the cap spindles to be individually put into driving connection with the feed motion shaft 3 at will by throwing in 90 the respective clutches, thus causing the spindles to rise slowly. The clutch may be constituted by a resilient clutch sleeve adapted to be gripped into and released from frictional driving engagement with a collar 8 fast on the shaft 3 by a small cam handle or lever 9 (see Fig. 3), pivoted to a bolt 10 passing through lugs 11 on the clutch sleeve 4, this clutch lever being adapted, in the engaged position, to force the lugs 11 of the clutch 95 sleeve towards each other by a suitable face or projection formed on it, and thereby to grip the clutch sleeve into engagement, and being adapted, in the released position, to allow the lugs 11 of the resilient clutch sleeve 100 to move away from each other and thereby to release the clutch. The clutch can be engaged and disengaged by hand at any time as required, by means of the clutch lever 9. The clutch lever 9 can also be arranged and adapted 105 to disengage the clutch automatically at the top of the lift of the spindle. For this purpose it may be formed with a nose 12 which comes in contact with the top of the lug 6 on the spindle at about the end of the 110 rise of the spindle, whereupon the clutch lever is caused to turn on its pivot and allow the lugs 11 of the resilient clutch sleeve to move away from each other, thereby releasing the clutch. The clutch lever in Fig. 3 115 is seen still in the engaged position just prior to its nose coming into contact with the lug 6 to release the clutch.

13, 13 are thread guides arranged vertically above their respective cap spindles and 130

each preferably carried by a vertical rod 14 guided in the frame members 15, 16 and fixed at bottom to an arm 17 attached to the lower end of the spindle 1, so that the thread guide 5 rises with the cap spindle, thus maintaining the balloon at a constant height in relation to the cap 2, and hence at a constant tension.

The chasing motion is imparted to the cops or pirns by a series of short traversing bars 10 18 provided along the length of the métier, each corresponding to two adjacent cap spindles 1 which pass up through openings in the traversing bars 18 so that these can traverse the tubes, bobbins or the like on the cap spindles. The whorls 19 for rotating the cop or pirn tubes, bobbins or the like, and driven by cotton banding or the like (20 Fig. 1) from the whorl driving drum of the métier (21 Fig. 1), are carried on the traversing bars 18. They slide and rotate on the cap spindles 1 and impart their rotation to the cop tubes, bobbins or the like through suitable means, such for example as a sleeve or tube 19^a (see Fig. 7) fast with the whorl and rotating with it on the spindle and receiving the cop or pirn tube 22, bobbin or the like.

The bars 18 receive their traversing motion from a chasing motion shaft 23 extending the length of the métier and rotated at any appropriate speed (e. g. 30 to 80 revolutions per minute). The chasing motion is imparted to the respective bars 18 by cams 24 on the shaft 23, one for each traversing bar 18, these cams imparting the up and down traversing motion to the corresponding bars 18 through vertical rods 25 working in guides 26, 26 and fixed at top to their traversing bars 18 at a point between the two adjacent cap spindles 1, and provided at bottom with cam rollers 27 working on the cams 24. Means may be provided for preventing the followers or cam rollers carried by the rods 25 from jumping the noses of the cams, and for preventing the whorls from leaving the traversing bars on the down stroke. For instance, coiled springs 28 may be fitted round each vertical rod 25 between its bottom guide 26 and the end of the rod 25 carrying the cam roller, for the purpose of preventing the cam roller from jumping the nose of the cam, and retaining plates 29 may be provided on the traversing bars 18 and engaging over the flanges of the whorls 19 to prevent the whorls from leaving the traversing bars on the down stroke.

55 The cap spindles 1 may with advantage work in housings fixed to the front of the frame member 16 extending all along the front of the métier, the housings providing the guides 30 (see Figs. 4 to 6) in which the spindles work in their slow feed or lift, the spindles being free to move vertically, but being restrained from rotating by reason of the anchorage of the chains 5 to them and of the attachment of the spindles to the arms 17 carrying the thread guide rods 14. In the ar-

angement shown, the vertical guides for each pair of adjacent cap spindles are formed, as to one half of the guides, in a housing body 31 fixed to the frame member 16, and as to the other half, in caps or cover plates 32, 32 bolted resiliently on the housing body 31 with the interposition of loading springs 33, 33 or the like so as to give a firm grip on the spindles without holding them fast from vertical motion. The arrangement 75 is seen clearly in Figs. 4, 5 and 6 which show the spindle guides or bearings 30, 30 formed partly in the housing body 31 and partly in the cap 32 and completed when the caps are bolted on the housing body 31. Conveniently, the housing body 31 is also formed with the upper and lower guides 26 for the vertical rod 25 that transmits the traversing motion to the traversing bar 18.

The chasing motion shaft 23 and the feed 85 motion shaft 3 are driven at the required speeds by any suitable means. In the arrangement shown they are driven from the main driving shaft 35 of the apparatus (see Fig. 1) through a chain 36 gearing with a chain 90 wheel 37 (Figs. 1 and 2) on a shaft 37^a, from which the drive is transmitted to the chasing motion shaft 23 and feed motion shaft 3 through any ordinary or suitable train of gears which may be contained in a gear box 95 38 at the end of the métier. Means may be provided for rotating the feed motion shaft and/or the chasing motion shaft at different speeds as desired, for instance when dealing with different weights of yarn.

In operation, assuming the chasing motion shaft 23 to be imparting the rapid traverse to the whorls and cop or pirn sleeves, and the cap spindles 1 to be in driving connection through their clutches 4 with the feed motion 105 shaft 3, the threads fed from the métier by the feed roller 39 (Fig. 1) are wound into cops or pirns by the combined action of the chasing motion and of the slow lift of the spindles, and at the end of the lift of any 110 given spindle the spindle is released automatically from driving connection with the feed motion shaft 3 by its clutch and can be set down in its bottom position for commencing the winding of a new cop or pirn, the 115 wound cop or pirn being removed and a fresh cop or pirn tube, bobbin or the like being put on to the whorl sleeve 19^a in its place. The release of the cap spindle from the feed motion shaft 3 can also be effected by hand by 120 means of the clutch lever at any desired moment, so that if for any reason or interruption it should be required to doff a defective or incompletely wound cop or pirn, this can be done at any point of the spindle lift and the spindle be set down again in its bottom position for beginning a fresh cop or pirn. To doff a given spindle and start a fresh cop or pirn thereon, the spindle, declutched from the feed motion shaft 3 automatically at top 130

of the lift or by hand as explained, is set in its bottom position, the spindle cap 2 is removed and a fresh cop or pирн tube, bobbin or the like is placed on the sleeve or tube 19^a of the whorl (Fig. 7), the cap 2 is replaced on the spindle, the clutch 4 is engaged again and the thread is thrown on to the new cop or pирн tube, or bobbin. It will be seen that any given spindles of the métier can be doffed 10 while the others are in operation.

Referring now to the form of apparatus shown in Figs. 8 and 9, 40 represents the feed motion shaft and 41 the chasing motion shaft, these shafts extending all along the métier, 15 the feed motion shaft 40 being driven at a suitable slow speed and the chasing motion shaft 41 at a suitable speed for the traversing motion as before explained. 42 are the cap spindles with their detachable caps 43. 44 is 20 a fixed bar extending all along the métier and in which are fixed a row of tubes 45, 45 in which the cap spindles 42 are free to reciprocate vertically in the traversing movement, the spindles 42 passing up through the tubes 25 45. The whorls 46 with their sleeves 47 for receiving the cop or pирн tubes, bobbins or the like, are arranged to slide and rotate on the respective tubes 45 in which the spindles 42 reciprocate, the whorls 46 and cop or pирн 30 sleeves 47 for each pair of adjacent spindles 42 being rotatably supported on a short bar 48, each bar 48 being carried on a vertical rod or poker 49 which receives the slow building feed and is guided in the fixed bar 44 and in 35 the bottom frame member 44^a. The rapid traversing motion is imparted to each spindle 42 by a corresponding cam 50 on the chasing motion shaft 41 through the medium of a flat spring 51 or a spring mounted lever provided 40 with a cam roller 52, these springs being fixed to the frame at their rear end by clamping plates 53 bolted to a longitudinal frame member 53^a extending all along the métier; the springs engaging at their front end under 45 a shoulder or abutment 54 near the bottom of the spindle 42, the lower end of the spindle extending through the spring and being fitted with retaining nuts 55. The slow building feed motion is imparted to each 50 vertical rod 49 from the feed motion shaft 40 by a corresponding cam 56 mounted loose on an axle 57 in a bracket 58 on the frame, these cams engaging cam rollers 59 on the vertical rods and being each driven from the feed motion shaft 40 by a worm 60 on this shaft 55 gearing with a worm wheel 61 mounted on the axle 57 of the cam, and adapted to be clutched into and out of frictional driving engagement with the cam by means of a 60 milled hand nut 62 screwing on the outer end of the axle 57 and which, when screwed up against the end of the sleeve 56^a of the cam, clamps the cam and worm wheel together in driving engagement, and releases them from driving engagement when screwed 65

back. In operation the cap spindles 42 are traversed rapidly through the whorls 46 and cop or pирн sleeves 47 by the cams 50 of the chasing motion shaft 41, and the whorls 46 and their cop or pирн sleeves 47 are slowly raised by the engaged cams 56 driven from the feed motion shaft, so that the cops or pирns are formed by the combined motions, the threads being fed from the métier to the cap spinning devices as in the previous arrangement, and led to the caps through the thread guides (not shown in Figs. 8 and 9) above the spindles. At the top of the lift of any given bar 48 with its pair of cop or pирн tubes on which the cops or pирns have now been wound, the nose of the cam 56 having reached its highest point, the cam roller 59 on the vertical rod 49 will drop with the rod 49 and bar 48 to the bottom position. The wound cops or pирns can then be doffed and replaced by empty tubes, bobbins or the like, the cam 56 being unclutched from driving connection with the feed motion shaft. On again engaging the clutch the building feed for the given pair of whorls and cop or pирн tubes is 90 commenced again at the bottom of the feed, and so on. In case of a premature interruption in the winding, due to breakage of threads or other cause, the corresponding cam 56 can be unclutched from driving engagement and the given bar 48 be lowered to the bottom position for doffing the cop or cops concerned or otherwise dealing with the interruption.

It will be seen that with this arrangement 100 the starting and stopping of the building feed for the cops or pирns can be controlled for each pair of adjacent spindles independently of the others, so that the feed for the cops or for a given pair of spindles can be started at 105 the bottom of the feed independently of those of the other spindles. The fall of the bar 48 with the cops or pирns when the cam roller 59 drops on the cam 56 at the end of the lift can break the threads, but if desired, the bars 48 110 may carry pins such as 63 adapted to catch the revolving balloon of thread at or about the end of the rise of these bars and thereby break the threads.

It is evident that the invention is capable 115 of being embodied in various constructions, and the drawings and description are therefore intended to be illustrative and not as limiting the invention.

What we claim and desire to secure by Letters Patent is:—

1. Apparatus for spinning threads into cop-wound packages, comprising, in combination, devices for simultaneously twisting threads and winding the twisted threads 125 upon thread-carriers, device for imparting a rapid traversing motion to the twisting and winding devices, devices for imparting a slow building feed motion to the twisting and winding devices, and individually control- 130

lable devices for stopping and starting the slow building feed motions, each of said stopping and starting devices being arranged to control the building feed motion for not more than two of the twisting and winding devices.

2. Apparatus according to claim 1, comprising individually controllable devices for throwing the driving connections for the slow building feed motions into and out of gear.

3. Apparatus according to claim 1, comprising individually controllable clutches for throwing the driving connections for the slow building feed motions into and out of gear.

4. Apparatus according to claim 1, comprising means for automatically stopping the slow building feed motion when the package has been completed.

5. Apparatus according to claim 1, comprising a slowly rotating building feed motion shaft, and devices driven by said shaft and each adapted to impart the slow building feed motion to not more than two of the twisting and winding devices.

6. Apparatus according to claim 1, comprising a slowly rotating building feed motion shaft, mechanisms driven by said shaft and each adapted to impart the building feed motion to not more than two of the twisting and winding devices, and clutches for individually throwing said mechanisms into and out of gear.

7. Apparatus according to claim 1, comprising a rotary traversing motion shaft, and devices driven by said shaft and each adapted to impart the rapid traversing motion for not more than two of the winding and twisting devices.

8. Apparatus according to claim 1, comprising a rotary traversing motion shaft, traversing bars each adapted to impart the rapid traversing motion for not more than two of the winding and twisting devices, and each actuated by a corresponding mechanism driven by the traversing motion shaft.

9. Apparatus according to claim 1, comprising a rotary traversing motion shaft, traversing bars each adapted to impart the rapid traversing motion for not more than two of the winding and twisting devices, and each actuated by a corresponding cam driven by the traversing motion shaft.

10. Apparatus for spinning threads into cop wound packages, comprising, in combination, cap spinning devices, means for imparting a rapid traversing motion to the cap spinning devices, means for imparting a slow building feed motion to the cap spinning devices and a number of individually controllable devices for stopping and starting the slow building feed motions, each of said stopping and starting devices being arranged to control not more than two of the cap spinning devices.

11. Apparatus for spinning threads into cop wound packages, comprising, in combination, cap spinning devices, means for imparting a slow building feed motion to the cap spinning devices, individually controllable devices for stopping and starting the slow building feed motions and each arranged to control not more than two of the cap spinning devices, and devices for imparting a rapid traversing motion to the cap spinning devices, each adapted to impart the rapid traversing motion for not more than two of the cap spinning devices.

12. Apparatus for spinning threads into cop wound packages comprising, in combination, cap spinning devices, a slowly rotating building feed motion shaft, devices driven by said building feed motion shaft and each adapted to impart the building feed motion for not more than two of the cap spinning devices, individually controllable devices for throwing the driving connections for the building feed motions into and out of gear, a rotary traversing motion shaft, and devices driven by said traversing motion shaft and each adapted to impart the rapid traversing motion for not more than two of the cap spinning devices.

13. Apparatus for spinning threads into cop wound packages comprising, in combination, cap spinning devices, a slowly rotating building feed motion shaft, mechanisms driven by said building feed motion shaft and each adapted to impart the building feed motion for not more than two of the cap spinning devices, individually controllable clutches for throwing the driving connections for the building feed motions into and out of gear, a rotary traversing motion shaft, and traversing bars each adapted to impart the rapid traversing motion for not more than two of the cap spinning devices; and each operated by a corresponding mechanism driven by the traversing motion shaft.

14. Apparatus for spinning threads into cop wound packages, comprising, in combination, cap spinning devices including spindles and thread carrier supports, means for imparting a rapid traversing motion to the thread carrier supports, means for imparting a slow building feed motion to the cap spindles and thereby causing the cap spindles to travel slowly through the traversing thread carrier supports, and individually controllable devices for stopping and starting the slow building feed motion, each of said stopping and starting devices being arranged to control not more than two of the spindles.

15. Apparatus for spinning threads into cop wound packages, comprising, in combination, cap spinning devices including spindles and thread carrier supports, means for imparting a rapid traversing motion to the thread carrier supports, means for imparting a slow building feed motion to the cap

- spindles and thereby causing the cap spindles to travel slowly through the traversing thread carrier supports, individually controllable devices for stopping and starting the slow building feed motion and each arranged to control not more than two of the spindles, and thread guides disposed vertically above the respective cap spindles and arranged to travel with their respective cap spindles.
- 10 16. Apparatus for spinning threads into cop wound packages, comprising, in combination, cap spinning devices including spindles and thread carrier supports, means for imparting a slow building feed motion to the cap spindles and thereby causing the cap spindles to rise slowly through the thread carrier supports, individually controllable devices for stopping and starting the slow building feed motion of each spindle independently of the other spindles, and means for imparting a rapid traversing motion to each pair of thread carrier supports.
- 15 17. Apparatus for spinning threads into cop wound packages comprising, in combination, cap spinning devices including spindles, a slowly rotating building feed motion shaft, and clutches on said shaft, one for each cap spindle and each connected by a flexible connection with the corresponding cap spindle.
- 20 18. Apparatus for spinning threads into cop wound packages comprising, in combination, cap spinning devices including spindles, a slowing rotating building feed motion shaft, and clutches on said shaft, one for each cap spindle and each connected by a flexible connection with the corresponding cap spindle, and means for effecting the disengagement of the clutches automatically at the end of the building feed of the spindles.
- 25 19. Apparatus for spinning threads into cop wound packages comprising, in combination, cap spinning devices including spindles, a slowly rotating building feed motion shaft, clutches on said shaft, one for each cap spindle and each connected by a flexible connection with the corresponding cap spindle, and thread guides disposed vertically above the respective cap spindles and arranged to rise together with their corresponding cap spindles.
- 30 20. Apparatus for spinning threads into cop wound packages comprising, in combination, cap spinning devices including spindles, devices for imparting a slow building feed motion to the cap spindles, devices for stopping and starting the building feed of each cap spindle independently of the other cap spindles, a series of short traversing bars, each corresponding to two cap spindles passing up through openings in said bars; driven whorls carried on the traversing bars and adapted to slide and rotate on their cap spindles, transmitting the traversing motion from the cams to the traversing bars.
- 35 21. Apparatus for spinning threads into cop wound packages, comprising, in combination, cap spinning devices including spindles, devices for imparting a slow building feed motion to the cap spindles, devices for stopping and starting the building feed of each cap spindle independently of the other cap spindles, a series of short traversing bars, each corresponding to two cap spindles passing up through openings in said bars; driven whorls carried on the traversing bars and adapted to slide and rotate on their cap spindles; a rotary traversing motion shaft provided with cams, one for each traversing bar; vertical rods working in guides for transmitting the traversing motion to the traversing bars; and means for preventing cam rollers carried by the vertical rods from jumping the nose of the cams.
- 40 22. Apparatus for spinning threads into cop wound packages comprising, in combination, cap spinning devices including spindles, devices for imparting a slow building feed motion to the cap spindles, devices for stopping and starting the building feed of each cap spindle independently of the other cap spindles, a series of short traversing bars, each corresponding to two cap spindles, passing up through openings in said bars; driven whorls carried on the traversing bars and adapted to slide and rotate on their cap spindles; a rotary traversing motion shaft provided with cams, one for each traversing bar; vertical rods for transmitting the traversing motion from the cams to the traversing bars; and means for preventing the whorls from leaving the traversing bars on the down stroke.
- 45 23. Apparatus for spinning threads into cop wound packages, comprising, in combination, cap spinning devices including spindles, a slowly rotating building feed motion shaft, clutches on said shaft, one for each cap spindle and each connected by a flexible connection with the corresponding cap spindle; and housings providing guides in which the cap spindles work in their slow building feed, the spindles being free to move vertically in the housings but being restrained from rotating.
- 50 24. Apparatus for spinning threads into cop wound packages, comprising, in combination, cap spinning devices including spindles, a slowly rotating building feed motion shaft, clutches on said shaft, one for each cap spindle and each connected by a flexible connection with the corresponding cap spindle; and housings providing guides in which the cap spindles work in their slow building feed, the spindles being free to move vertically in the housings but being restrained from rotating, said housings comprising a fixed housing body portion and a cap portion resiliently secured on the front of the housing body por-

tion, said housing body portion and cap portion being respectively formed with a portion of the vertical guide for the spindle.

25. Apparatus for spinning threads into cop wound packages, comprising, in combination, cap spinning devices including spindles, a building feed motion shaft, short bars carrying the whorls appertaining to each pair of adjacent cap spindles, vertical rods, one for

each of said short bars, and individually controllable clutches on the feed motion shaft, one for each vertical rod and each connected by a flexible connection with the corresponding rod.

In testimony whereof we have hereunto subscribed our names.

EDWARD KINSELLA.

HARRY EDWARD BELLAIRS YOUNG.
